PREWELT SHOE MANUFACTURE

Edward L. Sawyer, Washington, D. C., assignor to
 United Shoe Machinery Corporation, Flemington, N. J., a corporation of New Jersey

Application December 17, 1941, Serial No. 423,264

1 Claim. (Cl. 12—142)

This invention relates to the manufacture of prewelt shoes and is herein illustrated in its application to methods of holding a prewelt upper in pulled-over position on a last.

It is usual practice in the manufacture of prewelt shoes to secure the forepart of the prewelt upper in pulled-over position on the last by means of tacks driven through the welted margin of the upper and into the bottom of the last. The driving of these tacks and their removal upon the completion of the lasting operation constitute a considerable item in the labor cost entering into the manufacture of this shoe. These tacks must be driven between the welt-attaching seam and the inner edge of the welt in order that the tack holes will not be seen in the finished shoe and by reason of the very limited space in which the tacks may be driven, it frequently happens that one of these tacks severs the welt-attaching seam. Inasmuch as this is a chainstitch seam, any pressure by the foot of the wearer on the upper in the region of the break is likely to cause a considerable number of stitches adjacent to the break to loosen, thus irreparably crippling the shoe. The use of tacks is also objectionable because of the damage to the last bottom caused by the constant driving of tacks into substantially the same spots on the last. The damage thus caused to the last must be frequently repaired at a substantial cost to the shoe manufacturer.

It is an object of the present invention to do away with the use of tacks in the prewelt pulling-over operation. More specifically, the object is to provide a method of making prewelt shoes in which the upper will be held in pulled-over position on the last without the use of fastenings or the performance of any operation to secure the upper in pulled-over position.

With the above objects in view, the invention comprises a method of making prewelt shoes which consists in stitching a welt to the margin of an upper, in the course of the stitching operation securing the opposite ends of an elastic band to the welted margin at opposite sides of the shank portion of the upper, said band in its normal contracted position being shorter than the width of the shank portion of the bottom of the form on which the upper is to be lasted, mounting the upper on the last, pulling the toe end of the upper over the last, employing the tension of the elastic band to hold the upper in pulled over position on the last, and while the position of the upper on the last is maintained

by the band lasting the upper and completing the shoe.

The illustrated band is a piece of elasticized fabric but it will be understood that it matters little what material the band is made of as long as its contractile reaction to expansion exerts a pull strong enough to draw the welted margin at opposite sides of the shank portion of the shoe in against the inwardly curved side portions of the last, and strong enough to hold the side portions of the upper in inwardly drawn position after the pulling-over operation has been completed and until the upper has been lasted.

The invention will now be described with reference to the accompanying drawing illustrating the preferred construction and arrangement of elastic means connecting opposite sides of a prewelt upper.

In the drawing,

20 Fig. 1 is a bottom view illustrating a prewelt upper held in pulled-over position on a last by an elastic connector;

25 Fig. 2 is a perspective view showing the upper of Fig. 1 as it appears before it is mounted on a last; and

Fig. 3 is a section on the line III—III of Fig. 1.

The illustrated prewelt upper is of usual construction. The upper 10 (Fig. 2) is provided with a welt 12 extending about the entire periphery of the bottom margin of the upper, said welt being secured to the upper by a chainstitch seam 14 in accordance with the usual practice.

In the course of the welt-attaching operation, a band of elastic fabric 16 is secured by the welt-attaching stitches to the inner surface of the bottom margin of the upper at opposite sides of the shank portion of the upper. As illustrated in Fig. 2, the band 16 is arranged to extend widthwise of the shoe and its opposite margins 18 are

40 upturned and so positioned that the edges of said band coincide with the inner edges of the welt 12. When the band 16 is in its normal contracted position, those portions of the welt at opposite sides of the shank are held closer to each other than they are located in the finished shoe. Thus, in inserting the last 20, illustrated in Fig. 3, into the upper, the elastic band is expanded somewhat. The contractile reaction of the elastic band to its expansion will, of course, urge the welted

50 margin at opposite sides of the shank inwardly toward the center of the last bottom. It will be seen that in urging the welted margin inwardly, the band creates or maintains an inward curvature in the welted margin at opposite sides of the upper. Thus, the toe and heel portions of the

welted margin of the upper are drawn toward each other and held tight against the last.

In the manufacture of prewelt shoes in accordance with the method of the present invention, a prewelt upper provided with the elastic band 16 is held by the shoemaker in a convenient manner and a last is inserted into the upper through the bottom opening at the forepart of the upper and forced beneath the band 16 and into the heel portion of the upper, said band expanding to the extent required to admit the last into the upper. The last with the upper mounted thereon is then supported on a bench spindle and the forepart of the upper is pulled-over the last in any convenient manner, for example, by means of the usual hand lasting pincers. Inasmuch as the welt 12 is slightly shorter than the periphery of the bottom face of the last, the elastic band 16, urging the welted margin in against the inwardly curved side portions of the last bottom, will take up the slack created in the welted margin by the pulling-over operation and will hold the welt in taut condition on the last thereby holding the welted margin at the toe end of the upper in over the margin of the last bottom. Thus, it will be seen that the forepart of the upper will be held in pulled-over position on the last by the tension of the band 16 and no tacks or other fastening means will be required to secure the welted margin in position for the lasting operation. Conversely, it will also be understood that if the upper were not provided with the band 16 the opposite side portions of the welted margin of the upper would

extend in straight lines from the heel to the ball portion of the last bottom after the pulling-over operation and the forepart of the welted margin of the upper would not be drawn inwardly over the bottom margin of the last by the tension of the welt and fastenings would be required to hold the upper in pulled-over position on the last.

The width of the elastic band 16 and its exact location lengthwise of the upper are not important, the only requirement being that a portion of the band be located at the narrowest point in the shank portion of the shoe bottom in order that the welted margin at that point will be drawn in tightly against the last.

Having thus described my invention, what I claim as new and desire to secure by Letters Patent of the United States is:

That method of making prewelt shoes comprising stitching a welt to the margin of an upper, in the course of the stitching operation securing the opposite ends of an elastic band to the welted margin at opposite sides of the shank portion of the upper, said band in its normal contracted position being shorter than the width of the shank portion of the bottom of the form on which the upper is to be lasted, mounting the upper on the last, pulling the toe end of the upper over the last, employing the tension of the elastic band to hold the upper in pulled over position on the last, and while the position of the upper on the last is maintained by the band lasting the upper and completing the shoe.

EDWARD L. SAWYER.
